SIGNORS, BY MESNE ASSIGNMENTS, TO T. H. SYMINGTON AND SON, INC., OF BALTI-
MORE, MARYLAND, A CORPORATION OF MARYLAND

BOLSTER

Application filed June 1, 1926. Serial No. 113,082.

The invention relates to body bolsters and side bearing constructions for use in railroad car trucks.

The principal object of the invention, generally stated, is to provide a novel structure embodying a peculiarly arranged mounting for side bearing rollers which are interposed between the truck bolster and body bolster for the purpose of permitting swivelling action of the bolsters with respect to each other as must occur in car travel.

An important object of the invention is to provide a side bearing construction and mounting which does not in any way necessitate the making of alterations in the structure of the truck bolster, means being provided in the body bolster for accommodating bearing members coacting with the side bearing rollers.

Another object of the invention is to provide yieldable means in the body bolster coacting with the bearing member therein for maintaining constant contact between the bearing members and the side bearing rollers and between the side bearing rollers and the bearing elements on the truck bolster cooperating therewith.

A more specific object of the invention is to provide a structure of this character embodying pocket members mounted within the body bolster and containing bearing members urged downwardly by a bank or banks of leaf or plate springs which are normally under little, if any, compression but which act to oppose yieldable resistance to relative rocking movement of the truck and body bolsters, thereby tending to prevent, or at least reduce, car roll or side sway.

Another object of the invention is to provide a side bearing structure between the end portions of the truck and body bolsters embodying cushioning means which will act to take up clearance which might otherwise exist between the parts, all the bearing surfaces being constantly in contact so as to prevent the delivery of any blows to the mechanism when any relative rocking movement of the truck and body bolsters occurs, all the parts being consequently relieved of

shocks, jars and strains and their length of life being therefore increased.

Still another object of the invention is the provision of an arrangement and construction of this character which may be built into already existing equipment without necessitating any changes whatsoever in the truck bolster and very little change in the body bolster.

An additional object of the invention is to provide a structure of this character which will be comparatively simple and inexpensive to manufacture and install, positive in action, efficient and durable in service, and a general improvement in the art.

With the above and other objects and advantages in view, the invention consists in the details of construction and arrangement of parts to be hereinafter more fully described and claimed, and illustrated in the accompanying drawings in which:

Figure 1 is a view showing one end of truck and body bolsters with the invention in applied position, the truck bolster being in elevation and the body bolster and side bearing structure being in longitudinal vertical section.

Figure 2 is a vertical cross sectional view taken on the line 2—2 of Figure 1 and looking in the direction of the arrows,

Figure 3 is a fragmentary vertical sectional view quite similar to Figure 1 but illustrating a slightly modified arrangement of plate or leaf springs.

Figure 4 is a view similar to Figure 1 but illustrating a modification in which the spring cushioning means is eliminated, and

Figure 5 is a vertical cross sectional view taken on the line 5—5 of Figure 4 and looking in the direction of the arrows.

Referring more particularly to the drawings, and especially Figures 1 and 2, the numeral 1 designates a truck bolster which may be of any ordinary or preferred type such as the standard ones now in common use. This bolster is shown as having a center bearing 2 and it is of course provided at each end with an extension 3, these extensions being adapted to be located within the window openings in the truck side frames and to be

supported by springs in the usual manner. It will be observed that the side frames and springs are not shown as they not only form no part of the present invention but are unnecessary to a clear understanding of the present structure. Near each end the bolster is provided at its top with a bearing member 4 which may be mounted in any desired manner and which extends transversely of the bolster. The bearing member 4 is preferably provided or formed with an inclined bearing surface 5 at the ends of which may be provided upstanding teeth or projections 6.

The numeral 7 designates the body bolster which is, in most respects, of the ordinary construction or which may be of some special construction if desired. This bolster may conveniently include channel sides 8 connected by the usual top plate 9 and a bottom plate 10, both being secured to the center sills 11 forming part of the car underframe. In the carrying out of the present invention the bottom plate 10 may be considered as provided with an opening 12 or it may be described as formed of spaced sections to define the opening 12.

Mounted within the body bolster 7 at the openings 12 therein are pocket members 13 preferably provided at their lower ends with outstanding flanges 14 underlying the bottom plate 10 and suitably secured thereto and to the outwardly extending lower edges of the channel sides 8. The walls of the pocket members most remote from the vertical axis of the bolster are formed or otherwise provided with depending portions 15 for a purpose to be described, reinforcing webs 16 being preferably provided for effecting stiffening thereof. These pocket members form part of side bearing structures to be described, though it should be understood that the body bolster is provided with the usual or any other suitable center plate 17 received within the center bearing 2 on the truck bolster.

In this form of the invention the underneath side of the top portion of the member 13 is shown as concaved or inclined to define supporting ledges 18 engaged by the ends of the uppermost one of a bank or banks of plate or leaf springs 19 which are located within the pocket and which engage upon the convex upper surface 20 of a bearing member 21 mounted for vertical sliding movement within the pocket in accordance with flexing of the springs 19 under varying load conditions or as the result of rocking or swaying tendency of the car. The lower surface 22 of the member 21 is preferably inclined, the inclination being opposite to but of the same pitch as that of the bearing surface 5 of the member 14. It is also preferable that the member 21 be provided at the ends of the surface 22 with depending projections or teeth 23.

Located between the bearing members 21

and 4 at both ends of the bolsters are rollers 24 preferably tapered, the pitch being such that the rollers will conformingly engage against the inclined bearing surfaces 22 and 5. Actually, the rollers may be of hollow formation, if preferred, and the ends thereof are represented as recessed at 25 for the reception of the teeth or projections 6 and 23 so that when relative swivelling movement of the truck and body bolsters occurs and they subsequently return to normal the rollers will be restored to central or normal position, as will be readily apparent.

In the form of the invention above described, the plate or leaf springs may be said to extend transversely with respect to the bolsters, the ledges 18 being at or toward the opposite sides of the body bolster. In Figure 3 there is illustrated a slight modification in which the pocket member 26 corresponding to the pocket member 13 has the undersurface of its top portion provided with ledges 27 located at the outer and inner portions of the pocket member relatively to the vertical axis of the bolster. The bank or banks of springs 28 in this instance may be considered as extending longitudinally of the body bolster. The member 29 corresponding to the member 21 engaging beneath the springs and upon the roller has its convex upper surface 30 arranged longitudinally of the body bolster. In every other respect this form of the invention is identically the same as that first described.

Under some circumstances, as for instance if it is desired to cut down the cost of the equipment, the cushioning means such as the leaf or plate springs above described may be omitted, and in Figures 4 and 5 there is illustrated a modification or variation in which the pocket member 31 is formed or otherwise provided with a wall element 32 braced by any desired arrangement of reinforcing webs 33, this wall element having an inclined lower bearing surface 34 corresponding to the above described inclined bearing surface 22 for engagement with the roller. In this instance the wall member 32 may be provided with projections or lugs 35 received within the recesses 25 in the roller. It should of course be understood that while only one end of the bolsters is disclosed in every instance, the structure is identically the same at both ends.

In the operation, it will be seen that when relative swivelling movement of the truck and body bolsters occurs, the rollers will rock or roll transversely with respect to the bolsters. However, owing to the provision of the projections, lugs or teeth engaging the recesses in the rollers the rollers will always return to their normal or central positions when the bolsters return to their normal or registering position. Obviously it will be impossible for the rollers to become displaced laterally. Any longitudinal displacement is prevented

in a similar manner especially as the rollers extend up into the pocket members mounted within the body bolster. Inasmuch as the rollers are received within the pocket members and actually extend upwardly beyond the bottom of the body bolster it is possible to employ rollers of greater diameter than would be the case if they were located entirely below the body bolster. The provision 10 of rollers of such large diameter is of considerable advantage as friction, when relative swivelling movement of the bolsters occurs, will be reduced. In every instance, the outward end thrust of the rollers is taken 15 by the depending extensions at the lower ends of the outermost walls of the pocket members.

In this particular device it is intended that the load be sustained by the center bearing, 20 the side bearings acting to give stability to the car. In that form of the invention wherein use is made of the banks or plates of leaf springs or other cushioning means embodied in the side bearing structures, there is obviously a yieldable resistance to any relative 25 rocking movement of the bolsters. There will be no clearance between the rollers and the bearing surfaces engaged thereby, all of the parts being maintained in positive contact at all times. It is of course true that if desired the plate or leaf springs may take the 30 initial load, in which event they would be maintained in flexed condition, the degree of flexure varying in accordance with variations in the pressure resulting from tendency of the car to roll or sway. As there is no clearance between the bearing elements and as the cushioning means is provided there will be 35 a total absence of hammer-like blows which occur in ordinary types of bearing devices. By eliminating such blows or impacts shocks and jars and consequent deterioration of the entire truck structure and accessories will be avoided, the life of the parts being consequently 40 prolonged. From the foregoing description and a study of the drawings it is thought that the construction, operation and advantages will be readily apparent to one skilled in the art without further explanation.

While we have shown and described a preferred embodiment of the invention, it should be understood that the disclosure is merely an exemplification of the principles involved 55 as we reserve the right to make such changes and modifications as will widen the field of utility and increase the adaptability of the invention provided such variations constitute no departure from the spirit of the invention or the scope of the claims hereunto appended.

Having thus described the invention, we claim:

1. The combination of a truck bolster carrying a bearing member, a body bolster hav-

ing a pocket near each end, a bearing surface within the pocket, and a roller located between said bearing member and bearing surface and extending upwardly into the pocket, the outer wall of each pocket being prolonged 70 downwardly below the bottom of the body bolster to provide a thrust bearing surface for the outer end of the roller.

2. The combination of a truck bolster carrying a bearing member on its top, a body 75 bolster having a pocket near each end, a bearing element within the pocket, and a roller located between said bearing member and bearing element and extending upwardly into the pocket, the surfaces of said bearing member and bearing element being oppositely inclined and the roller being tapered.

3. The combination of a truck bolster having a bearing member on its top at each end, 80 a body bolster, a pocket member mounted within each end portion of the body bolster and secured to the bottom thereof, the pocket member being provided with a bearing surface at an intermediate point, and a roller 85 engaging upon said bearing member and beneath said bearing surface.

4. The combination of a truck bolster having a bearing member on its top at each end, a body bolster, a pocket member mounted 90 within each end portion of the body bolster and secured to the bottom thereof, the pocket member being provided with a bearing wall spaced downwardly from its top, and a roller 95 engaging upon said bearing member and beneath said bearing wall, the roller being of greater diameter than the space between the bolsters.

5. The combination of a truck bolster, a bearing member mounted upon the top of 100 each end portion thereof, a body bolster, a pocket member mounted within each end portion of the body bolster, a bearing member vertically slidably mounted within each pocket member, cushioning means within the pocket above the bearing member therein and yieldably engaging the same, and a roller located between and engaging both bearing members.

6. The combination of a truck bolster, a bearing member mounted upon the top of 110 each end portion thereof, a body bolster, a pocket member mounted within each end portion of the body bolster, a bearing member vertically slidably mounted within each pocket member, cushioning means within the pocket above the bearing member therein and yieldably engaging the same, and a roller located between and engaging both bearing members, both bearing members being provided centrally of each end with a vertical projection, and the opposite end portions of each roller being recessed for the reception of said projections.

7. The combination of a truck bolster hav-

- ing a flat top, bearing members on the top near the ends, a body bolster, pocket members within the body bolster near the ends thereof, a bearing member slidably mounted within each pocket member, banks of plate springs within the pocket members for cushioning the second named bearing members, rollers located between the first and second named bearing members, and means on the bearing members engaging with the rollers for centering the latter and preventing longitudinal displacement.
8. The combination of a truck bolster provided with bearing members on its top near its ends, a center bearing on the bolster, a body bolster having a center plate engaged within said center bearing, pocket members within the body bolster near the ends thereof, bearing members slidably mounted within the pocket members, banks of plate springs within the pocket members engaging the slideable bearing members, the undersurfaces of the tops of the pocket members being provided with ledges at opposite sides, the uppermost ones of the springs having their ends engaging said ledges, said slideable bearing members having convex upper surfaces, and rollers mounted between said first named bearing members and said slideable bearing members.
9. The combination of a truck bolster provided with bearing members upon its upper surface, a centering bearing on said bolster, a body bolster having a centering plate concentric with said centering plate of the truck bolster, pocket members within the body bolster, roller bearing means extending into said pocket members, the bottom edge of the pocket member being formed with outstanding flanges attached to the body bolster bottom cover plate.
10. The combination of a truck bolster provided with bearing members upon its upper surface, a centering bearing on said bolster, a coacting centering bearing upon a body bolster said body bolster containing pocket members, within which are vertically and rotatably movable rollers engaging upper and lower wear and centering plates, the former within the pocket member and the latter upon the upper surface of the truck bolster, the pocket wear plate engaging resilient spring means, said means sustaining a certain car weight without engagement of the flat surfaces of the aforementioned centering bearings of the truck and body bolsters.
11. In combination, a truck bolster provided at its end portions with bearing members, a body bolster having top and bottom plates, the bottom plate having an opening above each of said bearing members, a pocket member mounted within the opening and extending the full height of the body bolster with its upper end abutting against the underside of the top plate thereof, said pocket

member having outstanding flanges secured to the underside of the bottom plate, a transverse element intermediate the top and bottom of the pocket providing a bearing surface, and a roller mounted between said bearing member and bearing surface.

12. In combination, a truck bolster provided at its end portions with bearing members, a body bolster having top and bottom plates, the bottom plate having an opening above each of said bearing members, a pocket member mounted within the opening and extending the full height of the body bolster with its upper end abutting against the underside of the top plate thereof, said pocket member having outstanding flanges secured to the underside of the bottom plate, a transverse element intermediate the top and bottom of the pocket providing a bearing surface, a roller mounted between said bearing member and bearing surface, said pocket member having its side walls beneath said transverse wall portion formed with projections extending downwardly, and said roller having recesses conformingly receiving said projections.

13. In combination, a truck bolster provided at its end portions with bearing members, a body bolster having top and bottom plates, the bottom plate having an opening above each of said bearing members, a pocket member mounted within the opening and extending the full height of the body bolster with its upper end butting against the underside of the top plate thereof, said pocket member having outstanding flanges secured to the underside of the bottom plate, a transverse element intermediate the top and bottom of the pocket providing a bearing surface, and a roller mounted between said bearing member and bearing surface, said pocket member being formed with transverse and longitudinal webs merging into the top thereof and into said transverse wall portion.

In testimony whereof we affix our signatures.

THOMAS H. SYMINGTON.
PERCY R. DRENNING.
